UNITED STATES PATENT OFFICE.

CHARLES R. MOORE, OF MAPLEWOOD, NEW JERSEY, ASSIGNOR TO WESTERN ELECTRIC COMPANY, INCORPORATED, OF NEW YORK, N. Y., A CORPORATION OF NEW YORK.

SOUND RADIATOR.

Application filed June 15, 1928. Serial No. 645,618

This invention relates to radiators and has for an object to provide a sound radiator which is simple in form and easy to manufacture. This is accomplished by providing a sound radiator, for instance, which is adapted to serve as a loud speaker in the form of a sheet of thin stiff material such as paper, which may if desired, be coiled up.

Referring to the drawings, Fig. 1 is a plan view of a sound radiator with an electric drive, therefor, and Fig. 2 is a side elevation of Fig. 1.

Referring in detail to Fig. 1, the electromagnetic drive 1 may be of the form shown and described in detail in Egerton Patent 1,365,898, January 18, 1921. This drive is suitably supported on a base 2 which carries two upright posts 3 and 4 which support bars 5 and 6. These bars, by means of bolts 7, serve to clamp one edge of the sound radiator 8 which is coiled up, and another edge of which is suitably fastened to the driving element 9 of the electric motor, for instance, by a bolt 10. The lateral edges of the sheet or diaphragm are unsupported and, are free to vibrate.

Electric currents received by the motor 1 vibrate the diaphragm 8 which gives off corresponding sound waves.

What is claimed is:

1. In combination, a sound radiator comprising a sheet of paper coiled in substantially spiral form, said spiral having an axial dimension greater than its diameter, means for holding the inner edge of the spiral stationary, and means for imparting vibrations representing sound to said sheet near the outer end of the spiral.
2. In combination a direct acting loud speaking sound reproducer for speech and music comprising a sheet of a plurality of turns of thin flexible material substantially in spiral form, and means for imparting longitudinal vibrations thereto at one edge thereof.

3. In combination, a direct acting spirally shaped diaphragm of greater width than diameter comprising a plurality of convolutions, driving means associated with the outer edge of the spiral, and mounting posts therefor secured to the edge at the inner end of the spiral.

4. In combination a direct acting spiral shaped diaphragm comprising a plurality of convolutions, driving means for imparting longitudinal vibrations thereto at the outer end of the said diaphragm and supporting means attached along the inner edge of the spiral diaphragm.

5. A direct acting sound reproducer for speech and music comprising a spiral shaped sheet of thin stiff material having its axial dimension greater than its diameter, and means for impressing longitudinal vibrations representing sound to a free edge of the sheet at one end of the spiral in the direction of the surface of the sheet at the place where the vibrations are applied.

6. A loud speaker comprising a sheet like sound radiator, a base member having means for rigidly holding one edge of said radiator stationary with respect to said base, and a driving means for said radiator mounted on said base and connected to another edge of said radiator.

7. A direct acting sound reproducer comprising a curved sheet like diaphragm, a base member, means mounted on one portion thereof for rigidly holding one edge of said diaphragm, and means mounted on another portion of said base for driving said diaphragm at another of its edges, the vibrational forces imparted by said driving means being applied in the direction of the surface of the diaphragm at the point of attachment of the driving means.

In witness whereof, I hereunto subscribe my name this 7th day of June A. D., 1928.

CHARLES R. MOORE.
